HAND PUMP SPRAYER

Filed Sept. 10, 1928

UNITED STATES PATENT OFFICE

MAX A. KOHN, OF HARRISBURG, PENNSYLVANIA

HAND-PUMP SPRAYER

Application filed September 10, 1928. Serial No. 305,054.

This invention relates to spraying devices of the type adapted to be secured upon the back of the operator for conveniently spraying trees, plants, etc.

In devices of this character, liquid is forced from a tank under pressure supplied by a hand pump, and in order to build up pressure the tank must be removed from its position on the back and after sufficient pressure has been built up it may be replaced. This requires considerable time and effort, and the primary object of the present invention is to overcome these and other disadvantages by providing means for building up and maintaining sufficient pressure within the tank while the latter is in position on the back of the operator and without stopping the operation of spraying.

Another object of the invention is the provision of novel means for securing the pressure tank within the liquid containing tank, together with a pump of novel construction which combines to make up a sprayer of simple and economical construction and use.

With the above and other objects in view, the invention further includes the following novel features and details of construction, to be hereinafter more fully described, illustrated in the accompanying drawing and pointed out in the appended claim.

In the drawing:—

Figure 1 is a view partly in section and partly in elevation illustrating the invention.

Figure 2 is a plan view of the cover plate with the lever supporting arm in section.

Figure 3 is a detail view of one of the eye bolts.

Referring to the drawing in detail where-in like characters of reference denote corresponding parts, the reference character 10 indicates the main tank which is adapted to contain a liquid for use in spraying. The tank is adapted to be supported upon the back of the operator and for this purpose is provided with a saddle 11 which engages the back and with straps 12. One of these straps is shown and has its upper end secured to the tank as shown at 13 while its

lower end carries a hook 14 for detachable engagement with the saddle. The length of the strap is adjustable as shown at 15. When in use, the tank is positioned at the back of the operator, the straps 12 extending over the shoulders and beneath the arms with their lower ends engaged with the saddle 11 which rests across the back. This form of supporting the tank is common in devices of this character.

The tank may be reinforced by ribs 16 and its upper open end is provided with a flange or collar 17.

Removably positioned within the main tank 10 and extending downward through the upper open end is a pressure tank 18. This last mentioned tank is provided with a horizontally disposed flange 19 which engages over the flange 17 of the tank 10 and a gasket 20 is positioned between these flanges. The upper end of the tank 18 is closed by a cover plate 21 which has a flange 22 around its edge, this flange extending over the flanges 17 and 19 and the gasket 20. The plate 21 carries radially extending apertured ears 23 which receive eye bolts 24.

The bolts 24 removably engage studs 25 which are carried by the flange 17 and extend upward through the openings of the ears 23 and through spring washers 26. Thumb nuts 27 are mounted upon the upper ends of the eye bolts and bear upon the washers 26 to tightly clamp the plate 21 in position. This plate is also provided with a slot 28 for the passage of a discharge pipe 29, the latter extending downward into the pressure tank 18 and having its outer end connected with a flexible discharge tube 30 by means of a coupling 31. The outer end of the tube 30 carries a spray nozzle 32 and is provided with a valve 33 for controlling the discharge of liquid through the tube 30.

Located within the pressure tank 18 is a pump cylinder 34 whose upper end is secured to a partition 35 provided in the tank 18. This partition divides the tank 18 into a pressure chamber 36 and an air chamber 37, the latter communicating with the pump cylinder 34. A plunger 38 operates within the pump cylinder and is provided with a rod 39.

This rod extends upward through an opening 40 in the cover plate 21 and is pivotally connected with an operating lever 41. The lever 41 is pivotally mounted as shown at 42 upon a bracket 43 which extends upwardly upon opposite sides of the opening 40, the inner end of the lever 41 being bifurcated to engage over the upper end of the bracket 43 which is also bifurcated.

Depending from the pressure tank 18 is a nipple 44 having inlet ports 45 in its lower end. A passage 46 provided in the nipple communicates with the pump cylinder 34, a valve 47 controlling this passage. A passage 48 provides communication between the interior of nipple 44 and the pressure cylinder 18, the lower end of the passage 48 being provided with a check valve 49 which controls a port 50. A port 51 at the upper end of the passage 48 provides communication between this passage and the pressure cylinder or pressure chamber 36.

The outer end of the operating lever 41 has pivotally secured thereto one end of a rod 52 and the lower end of this rod is provided with a hand grip 53.

The apparatus is positioned upon the back of the operator as previously explained, the operating lever 40 extending forwardly over the left shoulder while the rod 52 extends downward in front of the operator with the grip 53 in convenient position to be grasped by the operator's left hand. By manipulating the lever 41, the pump plunger 38 is reciprocated and upon its upward stroke liquid from the tank 10 is drawn inward past the valve 47 through the passage 44 into the pump cylinder. During this movement of the plunger 38, the valve 49 will remain seated. Upon reverse or downward movement of the plunger 38, the valve 47 will be closed and the liquid which has previously been drawn into the pump cylinder will be forced outward through the passage 44 past the valve 49 and through the passage 48 into the pressure chamber.

This operation is repeated until sufficient pressure has been built up within the pressure chamber to force the liquid outward through the tube 30. After pressure has been properly built up, the sprayer will operate efficiently for a relatively long period of time without adding to the pressure within the pressure chamber. However, the lever 41 may be manipulated from time to time during the spraying operation to maintain proper pressure.

The invention is susceptible of various changes in its form, proportions and minor details of construction and the right is herein reserved to make such changes as properly fall within the scope of the appended claim.

Having described the invention what is claimed is:

1. In a spraying apparatus, a main liquid

containing tank, a pressure tank located centrally therein, and having a flange at its upper end reposing upon the upper edge of said tank, a cap closing both of said tanks and having a horizontally disposed slot opening at one edge thereof, a horizontal partition arranged within the pressure tank adjacent the top thereof, a cylinder located within the pressure tank, a flange on the upper end of said cylinder and supported by said partition, a supply pipe having its inner end located within the pressure tank adjacent the bottom thereof, said pipe being extended through the top of said tank and received by the slot of said cap, a piston operating within the cylinder, check valve controlled ports providing communication between the main tank and the pump cylinder, and between the pump cylinder and the pressure tank, a piston rod projecting through said cap, and means connected with the piston rod for operating the piston with the apparatus supported on the back of the user.

In testimony whereof I affix my signature.

MAX A. KOHN.
